SLICING MACHINE

William J. Campbell, Indianapolis, Ind., assignor
to American Slicing Machine Company, Chi-
cago, Ill., a corporation of New York

Application July 30, 1932, Serial No. 626,474

10 Claims. (Cl. 146—102)

My invention relates to an improvement in slicing machines and has for one purpose the provision of an improved pusher plate. Another purpose is the provision of improved means for locking such a pusher plate in inoperative position to permit the manual feeding of the material being sliced toward the cutting plane. Another purpose is the provision of improved means for releasably positioning a guard plate forwardly 10 of the knife and adjacent the cutting plane. Another object is the provision of means for preventing the guard plate from being bent in or pushed against the knife. Another object is the provision of improved means for centering or positioning sharpening means for the knife. Other objects will appear from time to time in the course of the specification and claims.

I illustrate my invention more or less diagrammatically in the accompanying drawings, 20 wherein—

Figure 1 is a plan view with parts broken away;

Figure 2 is a front elevation;

Figure 3 is a vertical section on the line 3—3 25 of Figure 2;

Figure 4 is a partial top plan view;

Figure 5 is a section on the line 5—5 of Figure 3, illustrating parts in different position;

Figure 6 is an enlarged section on the line 30 6—6 of Figure 2;

Figure 7 is an enlarged section on the line 7—7 of Figure 2; and

Figure 8 is a front elevation of a guard plate.

Like parts are indicated by like symbols 35 throughout the specification and drawings.

Referring to the drawings, A generally indicates any suitable base having anti-vibrational pads or supports A¹ which rest upon any suitable supporting surface A², for example a counter or 40 the like.

B indicates a motor mounted on the base A and having a motor shaft B¹ and a pulley B² about which passes a belt B³.

C indicates a housing extension projecting upwardly from the base A. Associated with it is a flared sleeve C¹ terminating rearwardly in a generally cylindrical portion C². Positioned within the portion C², the details of which form no part of the present invention and are not indicated in detail herein, is any suitable bearing means for a knife shaft C³ on which is mounted a pulley C⁴ and the knife C⁵. As will be seen in Figure 1, the pulley is positioned within and is housed by the member C¹, but the cutting edge 55 of the knife C⁵ extends outwardly beyond it as

at C⁶, the rear face of the knife being notched or recessed as at C⁷, to receive and overlap the outer edge of the member C¹. Any suitable means may be employed to hold the knife and pulley in place for example the axial screw C⁹ 60 and the radially spaced screws C¹⁰. C¹² indicates an end wall of the upper housing projection C and C¹³ the rear wall. As shown in Figure 1, the rear wall is apertured as at C¹⁴ to permit the passage therethrough of the motor shaft B¹ 65 and of a portion of the motor housing B. As shown in Figures 1 and 2 the belt B³ passes about the knife pulley C⁴, the knife being thus rotated in response to rotation of the motor.

D indicates a shield positioned between the 70 knife transmission and the knife itself. It may seat for example against the inward projection D¹ on the end walls C¹² C¹³ and it extends well within the periphery of the cutting edge of the knife, preferably approaching the hub of the 75 knife as shown in Figure 1. The inner edge may seat against the ledge D², the member being apertured as at D³ to permit the passage of the hub of the knife therethrough. It may be held in place as by the screws D⁴. It serves as a shield 80 between the knife and the knife transmission, whereby no grease, drippings or scraps can penetrate to the transmission. Since it entirely surrounds the knife, within the periphery of the 85 knife, it will be clear that the centrifugal effect of the rotation of the knife will be to prevent the penetration of any such material sufficiently inwardly toward the axis of rotation of the knife to pass into the aperture D³.

The forward face of the upstanding housing 90 member C is closed as by the guard plate generally indicated as E. As shown in Figure 1 the axis of the knife is slightly tilted to permit the arcuate edge E¹ of the guard plate to penetrate a forward hollow E² of the knife and to lie substantially flush with the very slightly bowed cutting plane defined by the cutting edge of the knife. The guard plate carries a scraper E³ secured thereon in any suitable manner, for example by the adjusting screw E⁴. The lower edge of the 100 guard plate is notched as at E⁵ to seat upon supporting pins E⁶ which may be screwthreaded for adjustment into the base or frame. Each such pin may include a normally fixed lenticular guard plate engaging member E⁷ and an opposed movable lenticular member E⁸ thrust thereagainst as by the coil spring E⁹. As the opposed faces of the members E⁷ E⁸ are flared apart, it will be understood that the guard plate may be readily positioned thereupon, the opposed members hav- 110

ing, in response to action of the spring E^9 , a snap action permitting ready insertion of the guard plate, but gripping the plate when it is placed in position. The upper edge of the guard plate E is provided with ears $E^{10} E^{11}$ at right angles to the face of the plate proper, such ears overlying top horizontal portions E^{12} of the frame member C . They are slotted as at E^{13} in such fashion that when the plate is swung into the full line position of Figure 4 they pass about the screw-threaded securing pins G^1 which hold down the top cover plate G . The ears $E^{10} E^{11}$ are located at different levels and the guard plate is irregularly formed, to permit movement of a knife sharpening assembly which will later be described.

The plate E is outwardly offset at top and bottom, as at $E^{14} E^{15}$, in order to permit the arcuate edge E^1 to penetrate the forward hollow of the knife C^5 . The lower edge of the guard plate E is preferably outwardly bent as at E^{16} to facilitate its insertion between the engaging members $E^7 E^8$ when the upper edge of the guard plate is outwardly tilted for convenient insertion. This will be clear from Figure 3 in which the guard plate is shown, in dotted line position, tilted somewhat outwardly, and is shown in full line in closed position. The handle E^{17} may be employed for easy handling of the guard plate. In order to permit ready insertion and withdrawal of the ears $E^{10} E^{11}$, the top portion E^{12} of the frame member C and portions of the edge of the cover plate G may be bevelled as shown at E^{18} .

In order further to permit ready handling of the plate E I provide a spring clip F as shown in Figure 7 which includes a body portion F^1 secured to the top of the frame as by the locking screw E^{21} , and a rolled edge F^2 . The spring is so formed as normally to flex up into the dotted line position in which it is shown in Figure 6 to permit the plate readily to penetrate beneath it. One function of the spring F is to prevent the plate from working out at the top during use as the overhanging roll F^2 when it is in the full line position of Figure 6, serves as a positive locking means for holding the upper edge of the plate E in position.

The cover plate G overlies the spring F and may be drawn down into full line position as by rotation of the screw or thumb nut G^1 . When so drawn down it compresses the spring F into the full line position of Figure 6, thus completing the locking effect. It is provided with lugs G^2 which actually engage the spring F , extending somewhat downwardly below the normal under surface of the cover plate G and forming effective and sure clamping means for holding the spring F down in full locking position.

To provide an inner abutment for the upper edge of the guard plate E I employ a plate E^{19} , which is slotted as at E^{22} to receive an adjusting and locking screw E^{21} . As the slot E^{22} is inclined, the forward edge of the member E^{19} may be adjusted inwardly or outwardly in relation to the guard plate E and it serves as a limit to limit the inward movement of the guard plate and to permit its accurate adjustment in relation to the knife. Note that the locking screw E^{21} serves to secure both the spring F and the adjusting plate E^{19} upon the top portion E^{12} of the frame member C . The spring F is slotted as at F^3 to permit passage therethrough of the securing pin G^1 .

H indicates a unitary sharpening lever with an outer handle H^1 . Mounted along the lever and rotatable in relation thereto is the stone H^2

and the metallic burr removing disc H^3 . Yielding means are employed, for example the spring H^4 , for keeping the sharpening lever in intermediate position with the stone and the metal disc both out of contact with the knife edge. The operator may move the lever in either direction, against the pull of the spring H^4 . The cover plate G is upwardly offset as at H^5 , to give space for the sharpening assembly, and is apertured as at H^6 to permit the handle H^1 to extend outwardly therethrough. The lever H is pivoted concentrically with one of the securing members G^1 . Such member may be surrounded by a bearing sleeve H^7 . In order to permit adjusting of the pull of the spring H^4 I provide an adjustment plate or clip H^8 slotted as at H^9 which may be gripped by two securing screws H^{10} . The purpose of this adjustment is to permit the inner end of the spring to be so adjusted as to hold the lever H normally in such position that neither of the sharpening members H^2 or H^3 engages the knife edge unless the handle H^1 is positively moved in one direction or another. In order to limit the movement of the guard plate E toward the knife and to prevent any thrust against it from causing it to impinge against the knife I provide an anti-frictional fiber stud or spacing member indicated as I . It may be set for example in the securing screw C^9 . There is normally some slight clearance between the inner face of the plate E and the outer end of the abutment I but the parts are so proportioned that a thrust against the face of the plate E which might tend to deform it or push it against the knife will bring it into contact, instead, with the abutment I , thus protecting the knife and preventing the noise which would be caused by a metal to metal contact if the inner face of the guard plate did engage any part of the knife.

Positioned on the base, and forwardly of the knife, are the tracks $J J^1$, the outer track J^1 being mounted for example on outwardly extending arms J^2 . Movable along said tracks is a carriage member generally indicated as J^3 , which includes track engaging members $J^4 J^5$. Mounted on the carriage J^3 is the work receiving member which includes a main portion J^6 downwardly inclined forwardly toward the knife when the parts are in the position shown in Figure 2. Associated with it is another member J^7 , at right angles thereto. The portion of the member J^6 adjacent the cutting plane extends outwardly as at J^9 and terminates in a rolled edge J^{10} . There is also provided an aperture J^{11} with the rolled edges J^{12} . This aperture serves as a thumb-hold, the portion of the member J^6 between the rolled edges J^{10} and J^{12} serving as a readily graspable handle means. The fingers may be used to feed meat or pusher plate. $J^{13} J^{14}$ indicate a pair of tracks or pins mounted on the carriage J^3 , a portion of which J^{15} extends to the right of the work receiving member $J^6 J^7$, as shown in Figure 1. It is to this extending portion of the carriage that the pins $J^{13} J^{14}$ are secured, they being also supported at their outer ends by the bracket J^{16} . Positioned in general alignment with the inner track J^4 and somewhat below it is a stub-pin J^{17} , the purpose for which will later appear.

K generally indicates a pusher plate carriage structure which is mounted to slide on the pin J^4 as by the bearing sleeve K^1 . The bearing sleeve has connected to it an outwardly extending arm K^2 to which may be secured also the manual handle K^3 . The operator may with one

hand grasp both the handle K^3 and the rolled inner wall J^{12} of the slot J^{11} , when manipulating both carriage and pusher plate with one hand. Mounted at the end of the member K^2 is a headed bearing screw K^4 about which is rotatable the pusher plate proper K^5 with its work engaging points K^6 . The screw K^7 actually serves as the pivot, as shown in Figure 1. The plate K^5 is provided with an arcuate slot K^8 concentric with the screw K^7 which is penetrated by an abutment stud K^9 headed as at K^{10} whereby a limited rotation of the pusher plate K^5 is permitted about its axis. Yielding means, for example the coil spring K^{11} , are provided for normally rotating the pusher plate to one limit of its rotation, namely counter-clockwise rotation when the parts are in the position shown in Figure 2. That is to say, the spring K^{11} having one end K^{12} associated with the member K^2 and the other K^{13} associated with the pusher plate K^5 , tends normally to rotate the pusher plate in such fashion that the abutment K^9 K^{10} is engaged by the lower end of the slot K^8 . When the parts are in the position in which they are shown in Figure 2 this tendency is gravitally resisted. The pusher plate and its carriage are freely movable toward and away from the cutting plane but when the pusher plate carriage K reaches the end of the pin J^{17} it locks with the pin, through any suitable formation or aperture K^{14} , rotation of the pusher plate assembly being prevented. This is important, since when the pusher plate is close to the cutting plane its rotation upwardly may be undesirable, since it might contact outwardly extending portions of the frame cover plate or the like. As soon as the screw J^{17} is cleared, however, the pusher plate assembly is rotatable about the pin J^{14} . K^{20} is a fiber bearing or riding member for the outer edge of the plate K^5 , preventing a metal to metal contact of the pusher plate and work support and spacing the serrated lower edge of K^5 somewhat above the work engaging surface of the member J^6 . Rotation of the pusher plate carriage K is limited by the lug K^{21} in which is adjustably mounted an abutment screw K^{22} which engages the pin J^{13} as illustrated in full line in Figure 5.

In order to permit the pusher plate to be locked in inoperative position, as shown in dotted line in Figure 2, I employ a latch L in the form of a plunger thrust by the spring L^1 . It has a working plunger head L^2 having a main bevelled surface L^3 and a slight bevel L^4 at the opposite side thereof. The parts are so proportioned that when the pusher plate is swung into the dotted line position the latch surface L^3 rides over the pin J^{13} and locks on it. The slight bevel L^4 is valuable as having a locking or tightening and thus rattle preventing effect. L^5 is any suitable manual or finger operated handle whereby the plunger L may be moved into inoperative position to permit the pusher plate assembly to be swung back into the full line position of Figure 2. Preferably I so proportion the parts that when the pusher plate assembly is in dotted line position it has passed over its center of gravity and a manual movement is necessary not only to release the latch plunger L but to move the pusher plate assembly back over its center of gravity and into the operative or full line position of Figure 2. Note that in the operation of the plunger L , I provide a limit slot L^6 in the casting K .

I may employ a gauge plate M which may be actuated in any suitable manner in response to

movement of the manual control member M^1 . The details thereof form no part of themselves of the present invention.

I may also employ any suitable drip pan N removably mounted on the forward edge of the base A . 80

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing. 90

I claim:

1. In a slicing machine including a base, a knife thereon and means for actuating it, a guard plate for the forward face of said knife, a frame portion, extending upwardly from said base, adapted to support said guard plate, a cover plate overlying the frame portion adjacent the top of the guard plate, and means for securing said guard plate on said frame portion, including securing members adapted to receive the lower edge of the guard plate, a yielding locking member for the upper edge of the guard plate, comprising a leaf spring, positioned beneath the cover plate, adapted, when in one position, to override an upper portion of said plate when the plate is thrust toward the spring, and means, connected with the cover plate, for thereafter forcing said spring downwardly into locking position, said spring being provided with an element adapted to overlap an edge of said plate when the spring is in locking position. 100

- against movement, with said projection in guard plate locking position.
4. In a slicing machine including a base, a knife thereon and means for actuating it, a guard plate for the forward face of the knife, a frame portion extending upwardly from said base, adapted to support said guard plate and means for securing the guard plate to said frame portion and forwardly of the knife, said means including 10 securing members adapted to receive the lower edge of the guard plate, a yielding locking member for the upper edge of the guard plate extending outwardly above the edge of the guard plate, and including a terminal projection adapted 15 normally to depend below the upper edge of the guard plate, a cover plate and additional holding means connected with the cover plate adapted to hold said yielding locking member against movement, with said projection in guard plate 20 locking position, the upper portion of said guard plate being provided with a generally horizontal inward extension adapted to underlie said yielding locking member and cover plate.
5. In a slicing machine including a base, a knife thereon and means for actuating it, a guard plate for the forward face of the knife, a frame portion extending upwardly from said base, adapted to support said guard plate and means for securing the guard plate to said frame portion 30 and forwardly of the knife, said means including securing members adapted to receive the lower edge of the guard plate, a yielding locking member for the upper edge of the guard plate extending outwardly above the edge of the guard 35 plate, and including a terminal projection adapted normally to depend below the upper edge of the guard plate, a cover plate and additional holding means connected with the cover plate, adapted to hold said yielding locking member 40 against movement, with said projection in guard plate locking position, the lower edge of the guard plate being tiltably received by said first mentioned securing members.
6. In a slicing machine including a base, a knife thereon and means for actuating it, a guard plate for the forward face of said knife, a frame portion, extending upwardly from said base, adapted to support said guard plate, a cover plate therefor, and means for securing said 50 guard plate on said frame portion, including securing members adapted to receive the lower edge of the guard plate, a yielding locking member for the upper edge of the guard plate positioned beneath the cover plate, and means connected 55 with the cover plate for positively moving and holding said yielding locking member in firm locking position, said yielding locking member including a flexible body portion adapted to extend outwardly above the upper edge of the guard plate and a locking portion adapted, when in locking position, outwardly to overlap and to extend downwardly below the upper edge of the guard plate.
7. In a slicing machine including a base, a knife thereon and means for actuating it, a guard plate for the forward face of said knife, a frame portion, extending upwardly from said base, adapted to support said guard plate, a cover plate therefor, and means for securing said guard 70 plate on said frame portion, including securing members adapted to receive the lower edge of the guard plate, a yielding locking member for the upper edge of the guard plate positioned beneath the cover plate, and means connected with the cover plate for positively moving and holding said yielding locking member in firm locking position, said yielding locking member including a flexible body portion adapted to extend outwardly above the upper edge of the guard plate, and a locking portion adapted, when in locking position, outwardly to overlap and to extend downwardly below the upper edge of the guard plate, the guard plate, a yielding locking member for the upper edge of the guard plate positioned beneath the cover plate, and means connected with the cover plate for positively moving and holding said yielding locking member in firm locking position, said yielding locking member including a flexible body portion adapted to extend outwardly above the upper edge of the guard plate, and a locking portion adapted, when in locking position, outwardly to overlap and to extend downwardly below the upper edge of the guard plate, the lower edge of the guard plate being tiltably received by the first mentioned securing members.
8. In a slicing machine including a base, a knife thereon and means for actuating it, a guard plate for the forward face of said knife, a frame portion, extending upwardly from said base, adapted to support said guard plate, a cover plate therefor, and means for securing said guard plate on said frame portion, including securing members adapted to receive the lower edge of the guard plate, a yielding locking member for the upper edge of the guard plate positioned beneath the cover plate, and means connected with the cover plate for positively moving and holding said yielding locking member in firm locking position, and a handle member associated with an upper portion of the guard plate, adapted for the ready outward movement of the guard plate 100 when the locking means are released, the lower edge of the guard plate being tiltably received by the first mentioned securing members.
9. In a slicing machine including a base, a knife thereon and means for actuating it, a guard plate for the forward face of the knife, a frame portion, extending upwardly from said base, adapted to support said guard plate, a cover plate mounted on said frame portion adjacent the upper edge of the guard plate, and means for securing said guard plate on said frame portion forwardly of the knife, including securing members adapted to receive the lower edge of the guard plate, and a yielding locking member for the upper edge of the guard plate, said locking member being positioned beneath the cover plate, and means for moving said yielding locking member into locking position, said means being connected with the cover plate.
10. In a slicing machine including a base, a knife thereon and means for actuating it, a guard plate for the forward face of the knife, a frame portion, extending upwardly from said base, adapted to support said guard plate, a cover plate mounted on said frame portion adjacent the upper edge of the guard plate, and means for securing said guard plate on said frame portion forwardly of the knife, including securing members adapted to receive the lower edge of the guard plate, and a yielding locking member for the upper edge of the guard plate, said locking member being positioned beneath the cover plate, and means for moving said yielding locking member into locking position, said means being connected with the cover plate, said yielding means including a flexible spring body, said guard plate including a portion at an angle to the rest of the guard plate, extending inwardly beneath said cover plate.

WILLIAM J. CAMPBELL. 145
